CHARLES H. BOND, OF PHILADELPHIA, PENNSYLVANIA.

SPARK-PLUG.

1,192,602.

Specification of Letters Patent. Patented July 25, 1916.

Application filed October 4, 1915. Serial No. 53,891.

To all whom it may concern:

Be it known that I, CHARLES H. BOND, a citizen of the United States, residing at Philadelphia, in the county of Philadelphia, 5 State of Pennsylvania, have invented a new and useful Spark-Plug, of which the following is a specification.

My present invention consists of a novel construction of a spark plug in which the parts are constructed and assembled in a novel manner and wherein the insulation is of such nature that it is not liable to become injured or broken when the spark plug is being assembled with respect to the cylinder 15 or removed therefrom.

It further consists of a novel spark plug in which the central electrode is insulated from the casing in a novel manner.

It further consists of a novel spark plug 20 in which the conducting portions are insulated by nonconducting portions in such a manner that the spark plug will not short circuit due to the presence of oil, and which will not burn or collect carbon, thereby 25 largely increasing the reliability and durability of the spark plug.

Other novel features of construction and advantage will hereinafter more clearly appear in the detailed description.

30 For the purpose of illustrating my invention, I have shown in the accompanying drawing a typical embodiment which is at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a perspective view of a spark plug embodying my invention. Fig. 2 represents a sectional elevation of the 45 spark plug. Fig. 3 represents a section on line $x-x$ of Fig. 2. Fig. 4 represents the bottom plan view of the spark plug.

Similar numerals of reference indicate corresponding parts in the figures.

50 Referring to the drawings, 1 designates the body portion of a spark plug embodying my invention, and comprising a tubular casing having at its forward end the exteriorly threaded portion 2 which preferably

tapers toward the forward end of the body 55 portion.

3 designates the negative electrode having the end portions connected with the forward end of the body portion 1 and preferably at points diametrically opposite each other. The central or laterally extending portion of the negative electrode is preferably deflected so that it is slightly off center, as will be understood by reference to Fig. 4.

65 5 designates the positive electrode which is centrally arranged with respect to the bore 6 of the body portion 1 and near its lower end it is provided with a threaded portion 7, and above such portion it is provided 70 with a threaded portion 8, such threaded portions 7 and 8 having threads of different pitch or character. For example in the form illustrated, the threaded portion 7 is provided with left-hand threads while the 75 portion 8 is provided with right-hand threads.

80 9 designates an insulating member which preferably consists of a plug or block of heat resisting composition which is provided with an aperture 10 extending longitudinally therethrough and through which the central electrode 5 is adapted to pass. The forward end of the insulating member 9 is recessed, as at 11, in order to receive a 85 nut 12 having its threads adapted to engage with the threaded portion 7.

13 designates a nut carried by the central electrode 5 and adapted to engage the threaded portion 8, whereby the central 90 electrode 5 may be readily adjusted with respect to the insulating member 9 and this also serves to adjust the central positive electrode with respect to the negative electrode as will hereinafter more clearly appear.

14 designates an upper insulating body or member, preferably consisting of a block of fiber having the longitudinally extending aperture 19 therethrough slightly greater 100 in diameter than the diameter of the central electrode 5 so that the latter will freely pass therethrough.

20 designates a cap which serves to reinforce the outer end of the insulating member 14 and which is apertured to permit the central electrode to pass through it.

21 designates a nut in threaded engage-

ment with the threaded portion 8 of the central electrode and abutting against the cap 20.

- 22 designates a binding nut on the central electrode which serves to secure the conductor 23 in electrical connection with the central electrode 5. The upper or outer insulating member 14 has fixed thereto in any desired manner a sleeve 24 the lower end of which is exteriorly threaded, as at 25, and such threaded portion 25 is in engagement with the interiorly threaded portion of a cap nut 26. This cap nut 26 is fixed with respect to the sleeve 24, the coaxing threaded portion of such member preferably being slightly tapered to effect this result. The cap nut 26 has its forward end exteriorly threaded in order to engage the interiorly threaded portion 27 of the body portion 1.

28 designates a gasket between the insulating member 9 and the cap nut 26 and sleeve 24, and the forward face of said gasket is preferably coated with asbestos or similar material which is pressed against the rear end of the insulating member 9. Interposed between the forward portion of the insulating member 9 and the cylinder 29 of the body portion 1 is one or more gaskets 30, and the face next to the insulating member 9 is preferably coated with asbestos or similar material.

The forward end of the insulating member 14 is preferably chambered as at 31 in order to receive the nut 13. In the present instance in order to increase the insulating area of the member 9 I have shown it as provided with a forward extension 32 but it will be apparent that this may be dispensed with if desired and substantially the same results attained by extending the recessed portion 11 a farther distance toward the rear end of the insulating member 9.

The spark plug can be readily taken apart when desired by removing the cap nut 26 whereupon the central electrode 5, the outer insulating member 14 and the inner insulating member 9 and their adjuncts are bodily removed as a unit. When it is desired to longitudinally adjust the central electrode 5 in order to vary the distance of its forward end relative to the negative electrode, the nuts 22 and 21 are loosened whereupon the central electrode and the inner insulating member 9 are removed as a unit. The nut 13 is then loosened and the central electrode 5 rotated in the proper direction to adjust its forward end with respect to the insulating member 9. The nut 13 is then tightened and the parts are assembled as hereinbefore set forth.

In my present invention I have eliminated the necessity of employing any fragile or easily breakable material such as porcelain, since the outer insulating member 14 is pref-

erably constructed of a solid piece of fiber of insulating material which is not easily broken and which will not be injured by being accidentally hit by a hammer or wrench. The insulating member 9 which is within the casing when the parts are assembled consists of a composition which will not burn or crack and which is not affected by variations of temperature and cannot be accidentally broken.

It will now be apparent that I have devised a novel and useful construction of a spark plug which embodies the features of advantage enumerated as desirable in the statement of the invention and the above description, and while I have, in the present instance, shown and described a preferred embodiment thereof which will give in practice satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. A spark plug, comprising an insulating body of fiber, a metal sleeve surrounding said body, a plug at the forward portion of said body, an electrode longitudinally adjustable with respect to said body and plug, said electrode being carried by said plug and removable as a unit of structure with said insulating body and plug, means to secure said electrode in its adjusted position, a body portion, an electrode carried thereby, and means engaging said sleeve and body portion to secure said insulated body with respect to said body portion, said metal sleeve extending outwardly beyond said sleeve engaging means to form a protection for the insulating body of fiber.

2. In a spark plug, an insulating body, an electrode passing through said body, an insulating member at the forward end of said body, said electrode being removable as a unit with said insulating body and member, nuts contacting with opposite sides of the insulating member and in threaded engagement with said electrode to effect the relative adjustment of said electrode and insulating member, and means to fix said electrode with respect to said body.

3. In a spark plug, an insulating body, a sleeve on said body, an electrode extending through said body and having threads of different pitch thereon, nuts to engage the different threads, an insulating member through which said electrode passes and located between said nuts, whereby said member may be longitudinally adjusted on said electrode and means carried by said sleeve to fix said electrode with respect to said insulating body.

4. In a spark plug, a body portion, an insulating body, an electrode passing therethrough, an insulating member carried by said electrode, a sleeve fixed to the forward 5 portion of said insulating body, and a nut fixed to said sleeve and engaging said body portion to secure said insulating body and insulating member in position, said sleeve extending outwardly beyond said nut to 10 form a protection for said insulating body.
5. In a spark plug, an outer insulating body of fiber having an aperture extending longitudinally therethrough, a positive electrode extending through said aperture and 15 having a thread thereon, the thread at one end of said electrode being of a different pitch from the thread at the opposite end thereof, nuts engaging said threads, an insulating member having an aperture through 20 which said electrode passes and located between said nuts, said nuts serving to effect the longitudinal adjustment of said electrode and insulating member, means to fix said electrode with respect to said insulating body, a body portion adapted to receive said insulating member and said electrode, a negative electrode carried at the forward 25 end of said body portion, and means carried by said insulating body to secure it with respect to said body portion.
6. In a spark plug, an insulating body of fiber, an electrode passing through said body, an insulating member adjustably carried by said electrode near its forward end, a body portion adapted to receive said insulating member, a negative electrode carried by said body portion, and a nut operatively connected with said insulating body and engaging said body portion to secure 30 the parts in assembled position.
7. In a spark plug, an insulating body, a positive electrode extending therethrough, a sleeve fixed to the forward end of said insulating body, a nut fixed to the forward end 45 of said sleeve, an insulating member adjustably mounted on said electrode, a gasket between said nut and said insulating member, a body portion having a chamber to receive said insulating member and having 50 means to engage said nut, and a negative electrode at the forward end of said body portion.
8. In a spark plug, an insulating body, an electrode extending therethrough, an insulating member having its forward end recessed, means including a fastening device located in said recess to adjustably connect said insulating member with respect to said electrode, said electrode, insulating body and member being removable as a unit of structure, a body portion into which said electrode extends and adapted to receive said insulating member, an electrode at the forward end of said body portion, and means operatively connected with said insulating body to secure said insulating member in fixed position within said body portion.
9. In a spark plug, an insulating body, an electrode extending through said body, a nut operatively connected with said insulating body, an insulating member adjustably mounted on said electrode, a gasket between said member and said nut, a body portion with which said nut is adapted to engage, and an electrode carried at the forward end of said body portion.
10. In a spark plug, an insulating body, a positive electrode extending through said body and having threads of different pitch thereon, nuts engaging said threads, an insulating member between said nuts, the forward end of said insulating body being recessed to receive one of said nuts, said positive electrode, insulating body and insulating member being removable as a unit, a tubular body portion having a chamber to receive said insulating member, a gasket between said insulating member and said body portion, a negative electrode carried by said body portion, and means to fix said insulating body with respect to said body portion.
11. A spark plug, comprising a body portion adapted to receive an insulating member, a positive electrode carried wholly by said insulating member and adjustable with respect thereto, an insulating body through which the rear end of said positive electrode passes, a nut at the rear end of the positive electrode to maintain the insulating members in assembled position, and means to secure the insulating body with respect to said body portion.
